ELECTRICAL PRECIPITATOR

Norman W. Sultz, Scotch Plains, N. J., assignor
to Research Corporation, New York, N. Y., a
corporation of New York

Application August 13, 1951, Serial No. 241,538

8 Claims. (Cl. 183—7)

1

This invention relates to electrical precipitators and more particularly to electrical precipitators having a liquid-washed device in the lower portion thereof for recovering in liquid solution or liquid suspension the precipitated material removed from the precipitator electrodes. More especially, the precipitator of this invention is adapted to recover sulfate fly ash in the form of an aqueous solution from the exhaust gases of a recovery furnace burning black liquor from the digesters in a sulfate paper mill.

An object of the invention is to provide an electrical precipitator having an improved device for recovering precipitate in liquid form.

Another object is to provide in such a precipitator a liquid washed recovery device having no moving parts.

Another object is to provide an electrical precipitator of the foregoing type that is simple to build and operate and that requires a minimum of maintenance care.

Another object is to provide in such a precipitator an arrangement for reducing the foam that tends to be produced with certain washing liquids such as black liquor.

These and other objects of the invention are realized in an electrical precipitator having a casing, complementary extended surface and high tension electrodes mounted in a casing, a panel mounted in an inclined position in the casing and positioned to receive dust falling from the electrodes, the panel having a plurality of ruffles projecting upwardly therefrom, means for applying liquid to an elevated area of the panel, and sump means below the panel for receiving liquid from the panel.

The invention will be described in greater detail with reference to the drawings in which:

Fig. 1 is a diagrammatic view of a black liquor recovery system employing a precipitator in accordance with the invention;

Fig. 2 is an end elevational view of an electrical precipitator as used in the system of Fig. 1, parts being broken away;

Fig. 3 is a sectional view taken on the line 3—3 of Fig. 2; and

Figs. 4 and 5 show details of construction of weir pieces at the lower edge of the flow panels.

Referring to the drawings, particularly to Fig. 1 thereof, the black liquor recovery system shown includes a storage tank 10 for weak black liquor received through the conduit 11 from the digesters and pulp filters (not shown) of a sulfate paper mill. The weak black liquor is passed through a pipe 12 under control of valve 13 to

5 a conventional multiple effect evaporator 14 having the usual barometric condenser 15. In the evaporator 14, the black liquor is concentrated by evaporation of water therefrom to a degree at which the heavy black liquor can be burned. The heavy black liquor is conducted by a pipe 15 to a heavy black liquor storage tank 16.

10 Heavy black liquor from the storage tank 16 flows through a pipe 17 to a charging tank 18 and from thence through the line 19 to a furnace charging device 20 that introduces a spray of heavy black liquor into the recovery furnace 21. In the furnace, the heavy black liquor is burned. The lignin contained therein, together with other combustible material, is oxidized to provide heat that vaporizes the water of the liquor. The furnace action reduces the principal inorganic ingredient of the liquor, sodium sulfate, to sodium sulfide that is the principal component of the furnace ash 22 that is discharged into a dissolving tank 23. In the dissolving tank, the ash is dissolved in water to provide a solution that is subsequently purified and reused for digesting additional quantities of wood chips.

15 25 Hot gases from the furnace, containing water vapor and products of combustion of black liquor, also contain a small but significant burden of fly ash in suspension. This fly ash contains a large percentage of sodium sulfate which it is desired to recover from the gases before they are discharged into the atmosphere.

The hot gases are passed from the furnace through a disc evaporator 24 in which some of the sensible heat of the gases is used to concentrate a portion of the black liquor from the multiple effect evaporator 14. This portion of black liquor is fed to the disc evaporator through the pipe 25 under control of valve 26 and the concentrated black liquor from the disc evaporator 30 is sent to the heavy black liquor storage tank 16 through the pipe 27.

35 40 45 A fan 28 blows the moist, somewhat cooled, furnace gases through an electrical precipitator 29 to be described in greater detail hereinafter. In the precipitator, the gases are substantially relieved of their burden of sulfate ash and the cleaned gases pass by way of a flue 30 to a stack (not shown) for discharge to the atmosphere.

45 50 55 Fly ash precipitated in the electrical precipitator is dissolved therein black liquor and the solution is ultimately fed to the black liquor storage tank 16 through the pipe 31 under control of the valve 32. The black liquor used for dissolving the sulfate ash may consist of (1) heavy black liquor pumped from the storage

tank 16 through the pipe 33, (2) weak black liquor received from the storage tank 10 through the pipe 34, (3) recirculated black liquor fed from the pipe 31 through the return line 35, (4) a mixture of any two of (1), (2) and (3), or (5) a mixture of (1), (2) and (3). The system of valves shown is used to vary the proportions of the black liquor components making up the fly ash solvent.

The electrical precipitator, generally designated 29, is shown in detail in Figs. 2 and 3. Referring to these figures, the precipitator shown has a shell or casing 36 that may be of concrete construction. Gas inlet and outlet ducts 37 and 38 are provided and gas flows through the precipitator in the direction of the arrows of Fig. 3.

As is usual in such precipitators, a plurality of complementary extended surface electrodes 39 and high tension electrodes 40 are positioned in the casing. The extended surface electrodes 39 may take the form of a plurality of vertically disposed, horizontally spaced, parallel plates providing parallel ducts 41 through which flows the gas to be cleaned. The high tension electrodes 40 are discharge electrodes in the form of fine wires suspended in curtain formation in the gas ducts between adjacent plates. Each wire 40 has a tensioning weight 42 at the bottom that keeps the wire taut.

Those persons skilled in the art will readily understand that, in operation, gas to be cleaned is passed through the precipitator and a high electrical potential is applied across the complementary discharge and extended surface electrodes. Corona discharge occurs at the fine wire electrodes and particles suspended in the gas are charged and attracted by the inter-electrode field to the extended surface electrodes. The particles are deposited upon the extended surface electrodes. By vibrating or rapping the electrodes, or otherwise suitably cleaning them in the conventional way, the precipitate is dislodged from the electrodes and allowed to fall into the section of the precipitator beneath the electrodes.

In accordance with the invention, there is provided in the casing 36 beneath the electrodes and in a position to receive dust falling therefrom a device for dissolving or suspending the dust in a liquid medium. This device includes a zig-zag arrangement of riffle boards over which flows the solvent liquid and onto at least some of which falls dust from the precipitator electrodes. This arrangement effects rapid dissolution of the dust in the solvent and the dust is removed from the precipitator in the solvent liquid.

As seen in Fig. 2, the riffle board structure is symmetrical about a vertical plane running through the center of the precipitator; therefore, only one half of the structure will be described.

The uppermost riffle board includes an inclined panel 43 that slopes downwardly from near the center line of the precipitator towards one of the walls thereof. The angle of slope is not critical and may range from about 10° to about 35°. The panel 43 is provided with a plurality of upstanding riffles or cleats 44 that are arranged in spaced parallel relation down the slope of the panel to interrupt the smooth flow of liquid down the panel and cause turbulence in the liquid.

Solvent liquid is fed to the upper area of panel 43 from an overflow trough 45 that ex-

tends across the top edge of the panel and has a weir or lip 46 over which the liquid spills from the trough upon the panel. Weir 46 is adjustable and may be leveled to provide uniform liquid distribution throughout its length.

At the lower edge of the panel 43 is provided a dam having an upstanding lateral member 47 and a weir piece 48 attached thereto. Details of this construction are best seen in Figs. 10 and 15 wherein it is seen that the weir piece 48 is fastened to the member 47 by means of bolts 49 passing through vertically elongated bolt holes 50 in the weir piece and through circular close fitting bolt holes 51 in the lateral member 47. Owing to the elongated configuration of the bolt holes 50, the weir piece 48 may be leveled and thereafter bolted securely to the member 47.

As seen in Figs. 4 and 5, the lower edge 52 of the weir piece depends below the bottom of the panel 43 and is serrated throughout its length. This serrated construction provides a plurality of drip points along the lower edge of the weir piece and assures uniform flow of liquid from the weir piece to the immediately subjacent riffle board 53.

Riffle board 53 slopes from the outer wall of the casing 36 beneath the riffle board 43 inwardly to a point adjacent the center line of the precipitator. Riffle board 53 is similar in construction to the board 43 described hereinbefore. It is provided with cleats 44' and a dam at its lower edge including the weir piece 48.

Positioned below the riffle board 53 is another and similar riffle board 54 that slopes from the center towards the outer wall of the precipitator. The discharge dam including the weir piece 48' discharges solution or liquid to a sump 55 having a lateral trough 56 receiving the solution. Solution is discharged from the trough through the pipe 31.

Solvent liquid is introduced into the trough 45 through the inlet pipe 33 having a header 57 extending above and parallel to the trough, the header being equipped with a plurality of horizontally spaced outlet nipples 58 that distribute the liquid into the trough. Additional liquid, either solvent or plain water, may be introduced behind the riffle board discharge dams through headers 59, 60 and 61 having distribution nipples 62.

In operation in the recovery system of Fig. 1, gases from the recovery furnace are blown through the precipitator 29 that is energized in the usual manner. Sulfate ash is precipitated upon the collecting electrodes. Black liquor of the desired concentration is fed to the ash dissolving device through the pipe 33 and additional black liquor or water is fed through headers 59, 60 and 61 as may be desirable to increase liquid flow through the dissolver. Black liquor flows in a zig-zag path over the riffle boards 43, 53 and 54 and into the sump 55. In its flow down the riffle boards, the liquor is continually agitated and any sediment that tends to collect behind the dams is agitated into suspension by liquid introduced through the nipples 62.

Sulfate ash from the electrodes 39 and 40 falls into the black liquor flowing down the riffle board 43 and is carried along by the liquor and dissolved therein as the stream flows through the dissolving device. Solution is discharged through the pipe 31.

It will be noted that the tensioning weights 42 hang in close proximity to the uppermost riffle

boards. A strong electric field is set up between the highly charged weights and the grounded uppermost riffle boards and this field tends to break any foam that may form in the black liquor on the uppermost riffle boards and in the feed trough 45. Also, the concentration of the black liquor is maintained near the point at which it has a minimum foaming tendency.

From the foregoing description it is seen that the present invention provides an electrical precipitator that accomplishes in a simple way the objects of the invention.

I claim:

1. An electrical precipitator comprising a casing, complementary extended surface and high tension electrodes mounted in said casing, a panel mounted in an inclined position in said casing and positioned to receive dust falling from said electrodes, said panel having a plurality of riffles projecting upwardly therefrom, means for applying liquid to an elevated area of said panel and sump means below said panel for receiving liquid from said panel.

2. An electrical precipitator comprising a casing, complementary extended surface and high tension electrodes mounted in said casing, a panel mounted in an inclined position in said casing and positioned to receive dust falling from said electrodes, said panel having a plurality of riffles projecting upwardly therefrom, means including an overflow trough positioned adjacent the top of said panel for applying liquid to an elevated area of said panel, and sump means below said panel for receiving liquid from said panel.

3. An electrical precipitator comprising a casing, complementary extended surface and high tension electrodes mounted in said casing, a panel mounted in an inclined position in said casing and positioned to receive dust falling from said electrodes, said panel having a plurality of riffles projecting upwardly therefrom, means for applying liquid to an elevated area of said panel, an overflow dam positioned adjacent the bottom of said panel, and sump means below said panel for receiving liquid from said panel.

4. An electrical precipitator comprising a casing, complementary extended surface and high tension electrodes mounted in said casing, a panel mounted in an inclined position in said casing and positioned to receive dust falling from said electrodes, said panel having a plurality of riffles projecting upwardly therefrom, means for applying liquid to an elevated area of said panel, an overflow dam positioned adjacent the bottom of said panel, means for introducing additional liquid behind and adjacent said overflow dam, and sump means below said panel for receiving liquid from said panel.

5. An electrical precipitator comprising a casing, complementary extended surface and high tension electrodes mounted in said casing, a plurality of inclined panels mounted in zig-zag arrangement in said casing, the topmost of said panels being positioned to receive dust falling from said electrodes, said panels having riffles projecting upwardly therefrom, means for applying liquid to an elevated area of the topmost of said panels, means directing liquid from a lower area of each said panel to an upper area of the immediately subjacent panel, and sump means below the lowermost of said panels receiving liquid from the latter.

15 6. An electrical precipitator comprising a casing, complementary extended surface and high tension electrodes mounted in said casing, a plurality of inclined panels mounted in zig-zag arrangement in said casing, the topmost of said panels being positioned to receive dust falling from said electrodes, said panels having riffles projecting upwardly therefrom, means for applying liquid to an elevated area of the topmost of said panels, means including an overflow dam directing liquid from a lower area of each said panel to an upper area of the immediately subjacent panel, and sump means below the lowermost of said panels receiving liquid from the latter.

20 7. An electrical precipitator comprising a casing, complementary extended surface and high tension electrodes mounted in said casing, a plurality of inclined panels mounted in zig-zag arrangement in said casing, the topmost of said panels being positioned to receive dust falling from said electrodes, said panels having riffles projecting upwardly therefrom, means for applying liquid to an elevated area of the topmost of said panels, means including an overflow dam having a serrated lower drip edge directing liquid from a lower area of each said panel to an upper area of the immediately subjacent panel, and sump means below the lowermost of said panels receiving liquid from the latter.

25 8. An electrical precipitator as defined in claim 7 wherein the means for applying liquid to the topmost of said panels includes an overflow trough positioned adjacent the top of said panel.
